UNITED STATES PATENT OFFICE

GEORGE O. FROSTAD AND JAMES E. ANNEN, OF MILWAUKEE, WISCONSIN, ASSIGNORS
TO THE NATIONAL PAPER CAN COMPANY, OF MILWAUKEE, WISCONSIN, A CORPO-
RATION OF WISCONSIN

CAN-MAKING MACHINE

Application filed April 6, 1928. Serial No. 267,878.

This invention relates to can making machines, and particularly to machines for forming cans by inserting a flanged cap in a preformed can body and forming a closure joint. However, certain features of the invention have other applications. The invention is herein described as particularly applied to the manufacture of cans from paper.

Most of the paper can machines heretofore employed have been open to numerous objections. They have been relatively slow in operation and have been short-lived. They have also lacked the adjustability which is desirable in machines of this character. Their slowness in operation has been due to the failure to provide suitable automatic feeding and ejecting means, as well as suitable means for forming and inserting the flanged cap. Other difficulties have been encountered, due to the lack of proper means for locating the can bodies with respect to the working heads.

We provide a machine wherein the can body is mounted on a mandrel or mandrels, and moved in an orbital path—preferably a non-circular path lying in a vertically extending plane. A very desirable construction comprises a supporting table and a flexible means, such as a chain, extending above and below the table and around the ends. The mandrels are carried by this flexible member and therefore travel along the top of the table, around the ends thereof, and therebeneath. The flexible member is moved forward in a step by step manner. Provision is made for feeding can bodies to a mandrel as it lies at the end of the table, and means is provided at the other end for ejecting the finished cans. The steps of inserting the cap forming the closure joint and then reshaping the joint are carried out at successive heads arranged along the table. The table itself supports the mandrel bases so that a rigid support is insured.

The table is provided with locating means so as to insure proper positioning of the mandrels at the various stations. This locating means is separate from the means for advancing the mandrels along the table. The advancing means is, as above stated, effective

for operating in a step by step manner, and brake means is provided for preventing coasting and over-travel.

The table is adjustable toward and away from the heads so as to accommodate different sized cans. In addition to this, the mandrels themselves are grooved and arranged to accommodate stop rings so that mandrels of one size may be used for cans of the same diameter, but of a different height. This is particularly useful for making can covers.

The vertical adjustment of the table is effected by a single operation. Preferably jack screws are employed for raising or lowering the table and these jack screws may be employed as tie rods for the machine. The feed means is adjustable with the table and is operated therefrom. The feed means preferably comprises a trough adapted to receive can bodies fed from the side, and a reciprocable bobbin or pusher for feeding the can bodies to the mandrels. A shaper motion is preferably employed for operating the bobbin, the shaper crank and disk being mounted on the table. The shaft of the disk is connected to a drive shaft which extends in the direction of adjustment of the table, and slideable means is employed so that adjustments may be made without disturbing the driving connection or getting it out of time.

We provide cap feeding means, including a forming die adapted to form a flange on a flat disk of paper, and a plunger cooperating with this die so as to force the disk therethrough, and upon continued movement to insert the cap in a can body on a mandrel. The cap forming and inserting mechanism may be employed in connection with a feed device for supplying pre-cut disks, but we also provide for supplying strip material, and for cutting the blanks from this strip. A shear is provided for cutting up the scrap so that it may be readily disposed of. We also provide a stripper for insuring that the cap will not be pulled out of the container body upon return stroke of the plunger.

Our co-pending application, Serial No. 267,879 filed April 6, 1928, describes and claims a preferred form of feeding mecha-

90

95

100

nism for supplying precut disks. This mechanism is particularly desirable for can covers and the like, where printed matter is to be placed on the cap.

It sometimes happens that a completed can is not ejected, and we provide safety means which will stop the machine before the mandrel carrying the can starts on another cycle of operation. In addition to this we provide further safety means in the form of yieldable anvil jaws. Anvil jaws are necessary for supporting the can body from the outside during certain of the operations. Sometimes a double can body is supplied to the machine and fed onto a mandrel. When this occurs, the anvil jaws yield so that no breakage results.

We also provide an improved operating mechanism for the various heads whereby lost motion, wear and noise are eliminated or reduced.

In the accompanying drawings which illustrate the present preferred embodiment of our invention,

25 Figure 1 is a front elevation of the machine,
Figure 2 is an end view thereof,
Figure 3 is a top plan view to enlarged scale showing a portion of the feeding mechanism,

Figure 9 is a vertical section through the cap forming and inserting head,

50 Figure 10 is a side view illustrating the feed mechanism for the strip from which the caps are formed,

Figure 11 is a diagrammatic view showing the driving connections.

55 Figure 12 is a view illustrating the safety device, and

Figure 13 is a vertical section taken on the line XIII—XIII of Figure 1.

Figures 1 and 2 illustrate the machine as a whole. It comprises a base 2 having a standard 3 mounted thereon. The standard is provided with ways 4 on which a table 5 is mounted for vertical adjustment. The adjustment of the table is effected by jack screws 6 which extend to the top of the machine and are provided with heads 7 lying

over forks 8 on the standard. Each jack screw is provided with a worm wheel 9 engaging a worm 10 on a horizontal shaft 11 arranged to be rotated by a hand crank (not shown). Rotation of the shaft 11 is effective for rotating the screws 6 and moving the table up or down.

The table is provided with head sprockets 12 and foot sprockets 13, and chains 14 extend around these sprockets. The chains carry base blocks 15 on which are mounted mandrels 16 for accommodating the can bodies. The chains are moved in a step by step manner so that between feeding operations mandrels will lie in the positions of Figure 1. In Figure 1 a mandrel 16^a is shown in dotted lines ready to receive a can body.

Can bodies are fed from a trough 17 by a pusher or bobbin 18. The cans are fed side-wise to the trough 17 from a chute C (Figure 2). The bobbin is reciprocated by a feed mechanism, indicated generally by the reference character 19, mounted on the table 5.

After a can body has been fed to a mandrel, the chain is moved forward one step. This brings it to the position 16^b of Figure 1, immediately below a cap feeding station, indicated generally by CF (Figure 1). At this station paper is fed forward from a reel R (Figure 2), a disk is cut therefrom, flanged and forced into the open end of the can body.

After the flanged cap has been inserted in the can body, the mandrel is moved forward to a station J where a closure joint is formed. At the next step in the operation the mandrel is carried to a station S where the joint is shaped. The can is now completed, and when its mandrel reaches the position 16^c of Figure 1, it is ejected by compressed air.

The idle mandrels return to the feeding station along the under side of the table, passing the safety device indicated generally by the reference character 20. This device is effective for stopping the machine in case a can sticks on the mandrel.

Can feed mechanism

See particularly Figures 1 to 4 inclusive.

The trough 17 is bolted to a bracket 21. This bracket is provided with bolt holes 22 at different points along its length so that the position of the trough 17 may be changed for different sized cans. The bracket 21 is supported at the end adjacent the machine by the shaft 13^a of the foot sprockets 13. At its outer end it is carried by an upstanding jack screw 23 and a supporting bracket 23^a. The jack screw 23 makes a worm gear connection at the bottom with the shaft 11. This insures that the feed mechanism will be moved up and down with the table 5. Lock nuts 24 are provided on the jack screw 23 as well as on the jack screw 6 to lock the feed mechanism and the table in an adjusted position. The bracket 21 is slotted as indicated

at 25 to accommodate a slide member 26 on which the bobbin 18 is mounted. The bobbin 18 is secured to the slide 26 by a screw 27. The slide 26 is provided with a pin 28 on which is mounted a clamp member 29. The clamp member is bored to receive a crank rod 30 and a clamp screw 31 is provided so as to tighten the clamp member 29 in any desired position along the rod 30. The rod 30 is connected through a spring barrel 32 to a pin 33 carried in a slot 34 on an arm 35. The arm 35 is pivotally mounted on the table 5 as indicated at 36, and is provided with a slot 37 engaging a crank pin 38 on the crank 15 disk 38^a. The crank disk 38^a is carried by a shaft 39 journaled in the table 5. This provides a quick-return mechanism by which the bobbin is alternately moved toward and away from the mandrel in the position 16^a. 20 The spring barrel 32 provides a yielding connection in the drive so as to eliminate shocks. It is desirable that inertia forces in this mechanism be reduced to a minimum, and for this reason the bobbin is preferably 25 made of aluminum.

The trough 17 has a front plate 40 having an opening 41 therethrough. This opening registers with the mandrel 16^a and the shuttle is effective for feeding can bodies B there- 30 through. The bobbin 18 is provided with a chamfered pad 42 on its working face. This pad is adapted to enter the can body and assist in centering it. The edge of the can body is engaged by a buttress 43 on the working 35 face of the bobbin. The front end of the can body is guided by a tapered portion 44 in the opening 41 and each mandrel 16 is chamfered as indicated at 45 to insure that the body will be guided thereon.

40 In order to insure that the mandrel at 16^a shall lie in proper alignment with the bobbin 18, spring pressed pins 46 are provided. These pins are best shown in Figure 5^a. As will be seen from that figure, the pins 46 45 press outwardly against the base 15 of the mandrel and tend to maintain it in a truly vertical position between movements of the chains and mandrels. This results in holding the mandrel at 16^a in truly horizontal 50 position so as to be in correct alignment with the bobbin 18.

As previously stated, Figure 5^a is a section on a line displaced from the center line on which the section shown in Figure 5 is taken. 55 Although only one pair of spring pressed pins 46 is shown, it is to be understood that a second pair, symmetrically disposed with respect to the vertical axes of the mandrels, is provided to insure proper positioning of 60 the blocks 15.

Figures 2 and 6 show the driving connection for the shaft 39. The shaft 39 extends through the table 5 and at its rear end carries a mitre gear 47 meshing with a corresponding mitre gear 48. The mitre 48 is journaled in

a bracket 49 secured to the table 5. The mitre gear 48 makes a spline connection with a vertical shaft 50. This construction permits of the table 5 being adjusted to various positions without interfering with the drive. 70 The spline connection comprises a key 50^a, slidable with the mitre gear 48 and engaging a key-way in the shaft 50, as shown in Figure 6.

Mandrel supporting and feed means

75

See Figures 1 and 5 to 8 inclusive.

The head sprockets 12 are carried on a shaft 51. This shaft is provided with a keyed sleeve 52 on which is rotatably 80 mounted a gear wheel 53. The gear wheel 53 carries clutch teeth 54 in one side face, these teeth being adapted to engage corresponding teeth 55^a in a clutch member 55 which is slidable along the collar 52, but is 85 prevented from rotating relative thereto by a key 56. A compression spring 57 urges the clutch member 55 against the teeth 54. The clutch teeth are inclined on one face so that the parts make a ratchet connection, effective 90 for driving the shaft 51 in one direction, but permitting the teeth 54 to click over the teeth of the clutch member 55 when the gear 53 is rotated in the reverse direction.

The gear 53 is rotated first in one direction and then in another by a rack bar 58. The rack bar is guided in the table 5 and has an arm 59 pivoted to its upper end at 59^a. The arm 59 extends through a clamping block 60 (Figure 1) and a second arm 61 extends upwardly from this block. 95

The arm 61, at its upper end, is carried by a crank pin 62 on a gear 63. Rotation of the gear 63 is effective for reciprocating the rack and causing the step by step feed 105 movement. The clamping block 60 is provided so as to shorten or lengthen the connection between the crank pin 62 and the rack bar 58, thus permitting adjustment of the table and also providing for suitable timing of the drive. 110

One of the sprockets 12 carries a brake drum 64. A brake band 65 extends around this drum. One end of the band is fixed on a bracket 66 secured to the table 5 (Figure 115 8). The other end is carried by an adjusting bolt 67 secured to a brake operating lever 68. One arm of the brake operating lever 68 is provided with a roller 69 engaging a cam 70. The cam 70 is carried by the brake 120 drum 64 and has three lobes.

The rack bar 58 is effective for rotating the sprockets 12 through one third of a revolution on each stroke and therefore one complete lobe of the cam 70 will pass over the roller 69 during each stroke. The mandrels 16, and their base blocks 15, are rather heavy in the aggregate and when the machine is operated at high speed, the inertia of these parts tends to cause coasting and 125 130

over-travel. It will be appreciated that such coasting is possible as the teeth on the clutch member 55 will simply click over the teeth 54 in the gear 53. The purpose of the brake mechanism is to prevent this overtravel.

Figure 8 shows the position of the parts at the end of a stroke. It will be noted that the roller 69 is lying against the high point of one of the cam lobes. As soon as the 10 shaft 51 is rotated the roller will pass onto the low point of the succeeding cam lobe and the brake 65 will be released. As the stroke continues, increasing brake pressure will be supplied and the pressure will be at 15 a maximum during substantially the last half of the stroke. By properly setting the adjusting bolt 67 the braking effect can be so regulated that the mandrels will be brought to a smooth stop at the proper point.

It will be noted from Figures 5 and 6 that 20 during the top run of the chain, the base blocks 15 of the mandrels are supported directly on the table 5, so that the pressure at the various working stations is taken directly by the table and not through the chains. 25 On the bottom run the chains and the mandrels are supported on guides 71.

The base blocks 15 are provided with small 30 holes 72 on each side adapted to receive pins 73. These holes are spaced apart a distance corresponding to the pitch of the chains 14, and the pins 73 take the place of the chain pintles for the links through which the connection between the chains and the base 35 blocks is made. Stretch and wear of the chains is compensated for by substituting shorter links between adjacent base blocks. Reference to Figure 1 will show that 40 instead of the teeth in the head sprockets 12 and 13 extending all the way around the periphery of each sprocket, certain teeth are omitted. Because of this construction, only 45 links lying alongside the base block 15 are engaged by sprocket teeth. This permits of using the shorter substitute links above referred to between base blocks without any tendency of the chain to "climb" on the sprockets and thus interfere with the 50 operation.

Due to the fact that chains stretch, it is 55 necessary to provide some locating means for definitely positioning the mandrels at the stations. Such means is of value regardless of the type of drive employed for moving the mandrels from one position to another. The locating means is shown in detail in Figure 5. The table 5 is bored to receive stop members 74. These members are shouldered, as indicated at 77 and are held in place by 60 bushings 75. They are normally urged upwardly by springs 76. They have an inclined face 77 directed toward the can feeding end of the machine so that when they are engaged by a base block 15 they will be 65 depressed and will not interfere with the

travel of the base block across the table top. However, as soon as a base block travels over one of these stop members, the stop member will move upwardly until its shoulder engages the bushing 75. This is the position 70 shown in Figure 5.

Each stop member has a squared shoulder 78. In operation the rack bar 56 is set so as to terminate the feeding movement with the trailing edge of each base block a short 75 distance ahead of the shoulders 78. Means is provided for engaging the leading edges of the base blocks and forcing the blocks back against the shoulder 78, thus definitely positioning the mandrels under the heads of the 80 machine.

The means for urging the base blocks backwardly comprises pins 79 working in openings 80 in the table top. The pins extend below the table top and at their lower ends 85 are provided with wrist pins 81 engaging slots 82 in arms 83. The arms 83 are pivoted to the table at 84. Each arm 83 carries a roller 85 engaged by cams 86 and 87. The cams 86 are carried on the shaft 39, (Figure 90 6). The cams 87 are carried on a shaft 88 having a chain and sprocket connection 89 with the shaft 39. Rotation of the shaft 39 is effective for swinging the arms 83 in a vertical direction about the pivots 84, thus 95 moving the pins 79 above or below the table 5. The cams 86 are effective for positively moving the pins downwardly, while the cams 87 are effective for causing a positive upward movement. 100

The cams 86 and 87 are so timed that the pins 79 are moved upwardly just prior to the completion of a feeding stroke. The leading edges of the base blocks 15 engage the pins 79 just prior to the end of their travel. 105 By reason of the fact that the pins make only a loose connection with the arms 83, no harm is done by this engagement. It is resisted, however, by spring pressed blocks 90 lying in recesses below the top of the table 5. As 110 soon as the feeding stroke is completed, the springs behind the blocks 90 cause the pins 79 to press the base blocks 15 back against the shoulders 78, thus positioning the mandrels. 115

Mandrels

The mandrels 16 are each provided with 120 grooves 91. These grooves are arranged to accommodate rings 92 indicated by dotted lines in Figure 6. The rings are somewhat similar to piston rings, except that they project beyond the peripheral surface of the mandrel. They determine the distance a can body can be slid over a mandrel, and they 125 hold the can bodies in proper position for the operations which are to be performed. The several grooves adjacent the bottom of the mandrels are provided to take care of can bodies of different length. The grooves near 130

the top of the mandrels are provided in case it is desired to make can covers or very shallow cans.

Anvil jaws

5 See Figures 1, 2 and 6.

As above pointed out, it is necessary to support the can bodies from the outside during the steps of making the closure joint and reshaping it. For this purpose we provide a pair of anvil jaws 93 at each of these stations. The anvil jaws must be moved apart to permit of feeding the mandrels along the table 5, and then must be brought together prior to the operation of the heads. The anvil jaws are carried by brackets 94. There are two brackets and each of them carries one anvil from each pair. Each bracket 94 is secured to a slide 95 by a bolt 96. This arrangement permits of a slight swinging of the bracket 94 so that the pressure which is applied from the slide 95 will be properly distributed between the cams on the anvils at the stations J and S.

The slides 95 operate in guides 97 formed in the table 5. Each slide is provided with a pin 98 carrying a cam follower 99. The cam followers 99 engage the grooves of barrel cams 100. The barrel cams make a spline connection with the shaft 39—that is to say, they are rotatable with the shaft but are slideable therealong. Each barrel cam is urged toward the center of the table 5 by a helical spring 101, the movement being limited by the bearings 102 of the shaft. In normal operation the hubs of the barrel cams lie against these bearings and the parts are so proportioned that with the barrel cams in this position, a suitable pressure on the can bodies will be exerted by the anvil jaws 93. It sometimes happens that a can body of double thickness is supplied to the machine and placed on a mandrel. In this case, the springs 101 will yield, permitting the cams 100 to move along the shaft 39 and thus protect the parts from breakage.

Each anvil jaw carries a hardened steel block 103 adapted to be engaged by the machine heads so as to impart a final clamping action to the anvil jaws just before the joint is formed or reshaped.

Cap forming head

See Figures 1, 2, 9 and 10.

The cap forming head comprises an outer barrel 104, carrying a die member 105 at its bottom. This die member has an upper step 106 and a lower step 107. Paper in strip form is supplied from the roll R through a slot 108, immediately above the die member 105, and from this paper strip a circular blank is cut out and then flanged and forced into the can body.

The strip feeding mechanism comprises a pair of feed rolls 109 and 110 carried by a

bracket 111 secured to the barrel 104. The feed roll 109 is carried on a shaft 112. The shaft 112 carries a sprocket 113 connected through a chain to a sprocket 114 on a shaft 115. A chain tightener 116 is provided as shown in Figure 2. The feed roll 110 is mounted on a shaft 117, but is not keyed thereto. The shaft 117 is driven from the shaft 112 through gears 118. The shaft 117 carries a slotted disk 119 and bolts 120 extend through the slots of this disk into the feed roll 110. By adjusting the bolts 120, the angular position of the feed roll 110 relative to the feed roll 109 may be changed as desired.

The feed rolls 109 and 110 each have a low portion 121 extending around substantially half their periphery. The rolls are urged together by backing springs 122 for the shaft 117, but the bracket 111 is so formed that the low portions 121 of the roll will be spaced apart so as to permit of the paper passing freely therebetween. When the feed rolls rotate the high portions of the feed rolls are effective for gripping the paper and feeding it forward. This feeding will not be accomplished until the high portions of both of the rolls are in engagement with the paper.

It follows that by properly positioning the bolts 120 in the slots of the disk 119 so as to change the relative angular position of the feed rolls 109 and 110, the amount of feeding may be varied as desired.

With the strip of paper in position over the die block 105, the next step is the cutting of a blank from the strip. This is accomplished by a punch 123 mounted on the lower end of the sleeve 124 which works in the barrel 104. At its upper end the sleeve 124 is provided with cam followers 125 lying in the grooves 126 of face cams 127, mounted on the shaft 115. Upon rotation of the shaft 115 the sleeve 124 is moved downwardly, thus cutting a circular disk from the strip and causing it to lie on the shoulder 107.

The blanked out disk is engaged by a plunger 128. This plunger is carried by a ram 129 which is reciprocable inside the sleeve 124. At its upper end the ram 129 carries cam followers 130 operating in grooves 131 in the face cams 127. The plunger 128 is effective for forcing the disk through the bottom opening of the die block 105, thus forming a flanged cap. Continued downward movement of the plunger 128 forces the cap into the open end of a can body on a mandrel 120 at 16° (Figure 9).

With the cap inserted in the can body, the punch 123 and the plunger 128 are drawn upwardly by the cams 127. As a matter of precaution it is desired to positively engage the flanged cap while the plunger 128 is withdrawn so as to overcome any tendency of the cap to stick to the plunger.

For this purpose there is provided a stripper 132 lying in the bottom face of the plunger 130

128. The stripper 132 is carried on a stem 133. The stem is shouldered and a collar 134 is fitted against this shoulder. A compression spring 135 normally urges the stem upwardly and holds the stripper 132 within the recess provided in the bottom face of the plunger 128. At its upper end the stem 133 is provided with a follower roll 136 engaging a cam 137 on the shaft 115. This cam is so shaped that it holds the stripper against the cap while the plunger 128 is being withdrawn. Immediately after the plunger has been withdrawn from the cap, the cam 137 permits the spring 135 to move the stripper upwardly, thus raising the stripper, the plunger and the punch to top position and permitting further feeding of the strip.

The scrap material produced by the punching of caps from the paper strip is fed outwardly through a slot in the front of the barrel 104 and corresponding to the slot 108. Outside this slot there is provided a stationary cutting knife 138 and a cooperating shear blade 139. The shear blade 139 is carried by a bracket 140 secured to the sleeve 124. An opening is provided in the barrel for this purpose. On every downward stroke of the sleeve 124, the shear knife 139 moves downwardly and shears off the leading end of the strip, thus cutting it up into small pieces for more ready disposal.

Heads for forming and shaping closure joint

See Figures 1, 2 and 5.

35 The tools employed may be of any desired type. We have illustrated and described below tools of the type shown in the application of James E. Annen, Serial No. 123,049, filed July 17, 1926. The tools are carried by a 40 ram 141, reciprocable in guides 142 formed in the standard 3. The downward stroke of the ram is the working stroke, and maximum power is required at this time. The downward stroke is effected by cams 143 mounted 45 on a shaft 144. The cams engage follower rolls 145 carried by the ram 141. The return stroke is effected by a cam 146 bearing against a follower roll 147. The ends of this follower roll work in slots 148 in the ram structure and backing springs 149 constantly urge it against the cam 146. By reason of this construction, no other take-up mechanism is necessary and the return cam becomes effective as soon as the upward rise of the 55 cam 146 engages the follower 147. With lost motion thus eliminated, it is found that the machine works smoothly and quietly.

The ram is provided with an extension 141* working in guides 150 on top of the standard 60 3. This construction is desirable because it insures that the ram 141 will always operate in alignment with the mandrels 16 lying therebelow.

Figure 5 shows the tools in sufficient detail 65 for the purposes of this application. The

forming tool at the station J comprises a collapsible core made of segments 151 adapted to be rocked about a carrying ring 152. A ram 153 lies inside the segments 151.

When the head is moved upwardly, the ram 70 engages the inner portions of the segments and rocks them about the ring 152, thus collapsing the segmental guide. On a downward stroke of the ram, the bottom portions of the segments 151 engage the cap and the 75 segments then move to the position of Figure 5. They are forced outwardly to a slight degree by the ram 153. At this time the edge of the can body and of the flange are standing upwardly just as they were left by 80 the cap forming head, and as shown in Figure 9. A curling ring 154 rolls the edge of the can body and the cap flange together so as to produce a rolled joint. During this time hardened steel shoes 155 engage the blocks 85 103 on the anvil jaws and hold the can body 90 tightly clamped on the mandrel.

Upon the next upward stroke of the ram 141, the segments 151 are retracted and pulled 95 clear of the rolled joint. The cam is then moved over to the shaping station S where the anvil jaws are again engaged to clamp the can body. An internal guide 156 is moved against the top of the can and inside the 100 rolled joint, and a shaping ring 157 reshapes 105 the rolled joint, thus completing the can.

Stripping cans from the mandrels

See Figures 5 and 11.

When a mandrel reaches the horizontally 100 extending position at the left hand end of the table 5, as viewed in the drawings, the can thereon is stripped off by means of compressed air, (see Figure 5). The air is supplied through a pipe 158 extending into a 105 chamber 159 which is bored in the end of the table 5. A hollow plunger 160 is carried in the chamber 159 and is held therein by a bushing 161 threaded into the table. The plunger 160 is urged outwardly by a spring 162. 110 When a mandrel is moved to the position shown at the left hand end of Figure 5, the opening in the plunger 160 registers with a small hole 163 in the bottom of the mandrel. As shown in Figure 5, the end of the hole 115 163 is flared out so that a proper joint between the tip of the plunger 160 and the mandrel is insured.

In order to take care of wear and to make certain that a tight joint between the plunger 160 and the mandrel will be obtained, the bushing 161 is internally threaded and is provided with a hollow screw 160^a. It is the outer end of this screw which makes an actual engagement with the mandrel. By threading 125 it inwardly or outwardly relative to the plunger 160 proper, the desired degree of tightness in the joint can be obtained.

The hole 163 communicates with a pipe 164 extending to the top of the mandrel so that 130

compressed air supplied through the pipe 158 may pass through the top of the mandrel and thus blow the completed can off.

When a mandrel is moved into the position of the mandrel at the left hand end of Figure 5, the base 15 engages the outwardly projecting end of the screw 160^a, thus causing the screw 160^a and the plunger 160 to move inwardly against the compression of the 10 spring 162. As the mandrel moves to the position shown in Figure 5, the spring 162 forces the plunger 160^a outwardly so that the screw 160^a engages the mandrel and makes a sufficiently air-tight connection to insure that 15 the completed can will be blown from the mandrel.

The supply of compressed air to the pipe 158 is controlled by a valve 165. This valve has a stem 166 provided with an operating 20 lever 167. One end of the operating lever carries a cam follower roll 168 and the opposite end is provided with a spring 169. The follower 168 engages a cam 170 carried by the mitre gear 48. Upon every rotation of the 25 shaft 50 the valve 165 is opened for a moment, thus permitting air from any desired source to pass to a pipe 171. One branch 172 of the pipe 171 leads to the pipe 158. The other branch 173 leads to a flared nozzle 174. The 30 nozzle 174 is located adjacent the cap forming head CF and is so positioned that it will blow any loose dirt or paper dust off the top of the mandrel.

Driving means

See Figures 1, 2, 9 and 11.

The main drive is through a pulley 175 which acts both as a fly-wheel and a belt pulley. It is carried on a flanged sleeve 176 keyed 40 to a shaft 177. A compression flange 178 is provided on the side of the fly-wheel 175 opposite the flange of the sleeve 176. The sleeve 176 carries a hand wheel 179 by which the flanges may be squeezed together so as to 45 make a friction clutch. The shaft 177 carries a pinion 180 meshing with a gear 181 on the shaft 144. The shaft 177 also carries a cam 182 effective for operating a lever 183 (Figure 13) which is desirable for operating a 50 stripper in connection with certain types of closure tools.

The gear 181 makes a driving connection with the shaft 144 through a clutch 184. This clutch is operated by a rod 185 (Figure 1) 55 connected through a lever 186, through a foot treadle 187. The clutch 184 is of the positive type such as is employed on punch presses and the like, so that the cam 182 is never thrown out of time.

The shaft 144 carries a gear 188 meshing 60 with the gear 63 for operating the rack 58, whereby the feed mechanism is actuated. The shaft 144 also carries the cams 143 and 146 for operating the ram 141. A gear 189 on the 65 shaft 144 meshes with an idler gear 190,

which in turn meshes with a gear 191 on a shaft 192. The shaft 192 carries a mitre gear 193 meshing with a mitre gear 194 at the top of the shaft 50.

The shaft 144 has an extended portion 195 carrying a gear 196 which meshes with a gear 197 keyed to the shaft 115.

Safety device

See Figures 1 and 12.

In Figure 12 the direction of travel of the mandrels 16 on their return run below the table 5 is indicated by an arrow. A chain line around one of the mandrels 16 indicates a can which has not been stripped from the 80 mandrel. Continued movement of this mandrel will bring the can into engagement with a roller 198. The roller 198 is mounted on a lever 199 pivoted to a stationary switch member 200 at 201. The stationary switch member 200 is carried by a clamp 202 on a post 203 so that the switch may be adjusted to different positions depending upon the size of mandrel employed. Clamp means 85 204 is provided for adjusting the switch toward or away from the mandrels.

The switch lever 199 is normally urged toward the path swept out by the mandrels by a spring 205. This movement is limited by check nuts 206. The stationary switch 90 member 200 and the switch lever 199 carry electrical contacts 207. These contacts are normally out of engagement, but when the roller 198 is touched by a can body, an electric control circuit is closed, thus stopping the 95 machine.

While we have herein illustrated and described the preferred form of our invention, it will be understood that it is not limited to this form alone, as it may be otherwise 105 embodied within the scope of the following claims.

We claim:—

1. A can making machine comprising a mandrel, means for moving the same in an orbital path, means for feeding a can body to the mandrel during such movement, means for feeding a cap to the body, means for forming a closure joint between the cap and the body, and safety means lying alongside the path whereby the mandrel moving means may be stopped if the can is not removed from the mandrel before it starts another cycle.

2. A can making machine comprising a mandrel, means for moving the same so as to sweep out a path lying in a vertically extending plane, means for feeding a can body to the mandrel while it is in a horizontally extending position, and means for feeding a cap to the body while the mandrel is in a vertically extending position.

3. A can making machine comprising a mandrel, means for moving the same so as to sweep out a path lying in a vertically extending plane, means for feeding a can body 130

to the mandrel while it is in a horizontally extending position, means for feeding a cap to the body while the mandrel is in a vertically extending position, and means for forming a closure joint between the cap and the body while the mandrel is in a vertically extending position.

4. A can making machine comprising a mandrel, means for moving the same so as to sweep out a path lying in a vertically extending plane, means for feeding a can body to the mandrel while it is in a horizontally extending position, said feed means comprising a trough lying in alignment with the mandrel when it is in the feeding position, and a pusher working in the trough.

5. A can making machine comprising a mandrel, means for moving the same so as to sweep out a path lying in a vertically extending plane, means for feeding a can body to the mandrel while it is in a horizontally extending position, said feed means comprising a trough lying in alignment with the mandrel when it is in the feeding position, a pusher working in the trough, a drive connection for the pusher, and spring means in the driving connection.

6. A can making machine comprising a mandrel, means for moving the same so as to sweep out a path lying in a vertically extending plane, means for feeding a can body to the mandrel while it is in a horizontally extending position, said feeding means comprising a trough lying in alignment with the mandrel when it is in the feeding position, means for supplying can bodies from one side of the trough, and a pusher working in the trough.

7. In a can making machine, a mandrel, can body feeding means comprising a trough lying in alignment with the mandrel when it is in feeding position, gravity means for supplying can bodies to the trough from one side thereof, and a pusher lying in the trough, the pusher having stop means effective for restraining a can body from entering the trough during a feeding stroke of the pusher.

8. A can making machine comprising a mandrel, a support for the mandrel, means carried by the support for moving the mandrel so as to sweep out a path lying in a vertically extending plane, means for feeding a cap to the body, means for forming a closure joint between the cap and the body while the mandrel is in vertically extending position, and means for adjusting the support vertically to accommodate different sized cans.

9. A can making machine comprising a mandrel, a support therefor, means carried by the support for moving the mandrel so as to sweep out a path lying in a vertically extending plane, means for feeding a can body to the mandrel while it is in a horizontally extending position, means for feeding a cap to the body, means for forming a closure joint

between the cap and the body while the mandrel is in a vertically extending position, and means for adjusting the support vertically to accommodate different sized cans, the feed means being simultaneously adjustable with the support.

10. A can making machine comprising a station for forming a head in the can, a movable mandrel for conveying can bodies to the station, said mandrel being tiltable to different positions, and feed means for supplying can bodies to the mandrel when it is tilted with relation to its position at the station.

11. A can making machine comprising a station for forming a head in the can, a movable mandrel for conveying can bodies to the station, said mandrel being tiltable to different positions, feed means for supplying can bodies to the mandrel when it is tilted with relation to its position at the station, and spring operated backing means for positioning the mandrel during the feeding operation.

12. A can making machine comprising a mandrel, a support therefor, means for moving the mandrel on the support so as to sweep out a path lying in a vertically extending plane, means for feeding a can body to the mandrel while it is in a horizontally extending position, drive means for the feed means, means for feeding a cap to the body, means for forming a closure joint between the cap and the body while it is in a vertical position, and means for adjusting the support vertically to accommodate different sized cans, the feed means being simultaneously adjustable with the support and the drive means therefor being carried by the support and adjustable therewith.

13. In a can making machine, a table, a flexible member extending along the top of the table, around the ends thereof and therebelow, means for imparting a step by step movement to the flexible member, a mandrel movable with the flexible member, and a working station along the path of the mandrel.

14. In a can making machine, a table, a flexible member extending along the top of the table, around the ends thereof and therebelow, means for imparting a step by step movement to the flexible member, a mandrel movable with the flexible member, a feed station at one end of the table, and a working station above the table.

15. In a can making machine, a table, a flexible member extending along the top of the table, around the ends thereof and therebelow, means for imparting a step by step movement to the flexible member, a mandrel movable with the flexible member, a feed station at one end of the table, can ejector means at the other end, and a working station intermediate the ends.

16. In a can making machine, a table, a flexible member extending along the top of the

table, around the ends thereof and therebelow, means for imparting a step by step movement to the flexible member, a mandrel movable with the flexible member, and a working station along the path of the mandrel, the table being arranged to directly engage and support the mandrel structure when it lies in operative position at the station.

17. In a can making machine, a table, a flexible member extending along the top of the table, around the ends thereof and therebelow, means for imparting a step by step movement to the flexible member, a mandrel movable with the flexible member, a working station along the path of the mandrel, and locating means for definitely positioning the mandrel at the working station.

18. In a can making machine, a table, a flexible member extending along the top of the table, around the ends thereof and therebelow, means for imparting a step by step movement to the flexible member, a mandrel movable with the flexible member, a working station along the path of the mandrel, means limiting the return movement of the mandrel, and means urging the mandrel against such limiting means at the end of a feed stroke, the limiting means being so located as to properly position the mandrel with respect to the working station.

19. In a can making machine, a support, a flexible member extending along the support, means for imparting a step by step movement to the flexible member, a mandrel carried by the flexible member, a working station along the path of the mandrel, means limiting the return movement of the mandrel, and means urging the mandrel against the limiting means at the end of a feed stroke, the limiting means being so located as to properly position the mandrel at the working station.

20. In a can making machine, a support, a flexible member extending along the support, means for imparting a step by step movement to the flexible member, a mandrel carried by the flexible member, a working station along the path of the mandrel, means limiting the return movement of the mandrel, a pusher for urging the mandrel backwardly at the end of a stroke, and means for withdrawing the pusher from the path during the feed stroke.

21. In a can making machine, a support, a flexible member extending along the support, means for imparting a step by step movement to the flexible member, a mandrel carried by the flexible member, a working station along the path of the mandrel, means limiting the return movement of the mandrel, a member movable into or out of the path swept out by the mandrel, means controlling such movement, and spring means effective for pushing the member when it is in the path of the man-

drel so as to urge the mandrel backwardly against said limiting means.

22. In a can making machine, a support, a flexible member extending along the support, a mandrel movable with the flexible member, means for imparting a step by step movement to such flexible member, and brake means for preventing over-travel of said flexible member.

23. In a can making machine, a support, a flexible member extending along the support, a mandrel movable with the flexible member, means for imparting a step by step movement to such flexible member, brake means for preventing over-travel of said flexible member, and means for applying increasing braking pressure during a forward movement.

24. In a can making machine, a support, a flexible member extending along the support, a mandrel movable with the flexible member, means for imparting a step by step movement to such flexible member, brake means for controlling the movement of the flexible member, and cam means actuated upon a feed movement for controlling the brake means.

25. In a can making machine, a mandrel having a groove therein, and a ring fitting in the groove and determining the operative length of the mandrel.

26. A can making machine comprising a standard, closure forming means carried thereby, a shaft mounted on the standard for operating the closure forming means, a table carried by the standard, the table being adjustable toward or away from the closure forming means, a flexible member mounted on the table and carrying a mandrel, rack and pinion means for operating the flexible member, the rack being operatively connected to said shaft, and means in the rack connection for adjusting the length thereof.

27. In a can making machine, a plurality of mandrels movable in an orbital path, means for imparting a step by step movement to the mandrels, feed means for supplying can bodies to the mandrels, a station for working on a can body on a mandrel, locating means for definitely positioning a mandrel at the working station, and a shaft for bringing the locating means into operation, the feed means being driven from said shaft.

28. A can making machine comprising a frame, a ram thereon for effecting an operation on a can, a table adjustable toward and away from the ram, a supporting mandrel on the table for carrying the can being worked on and a tie rod for the frame extending in the direction of adjustment of the table, the tie rod being threaded and engaging the table.

29. A can making machine comprising a frame, a ram thereon for effecting an operation on a can, a table adjustable toward and away from the ram, a supporting mandrel on

the table for carrying the can being worked on, and a tie rod for the frame extending in the direction of adjustment of the table, the tie rod being threaded and engaging the table and rotatable so as to effect an adjustment of the table.

30. In a can making machine, a table, a flexible member extending therealong, a mandrel carried by the flexible member, and anvil jaws movable toward the path of the mandrel to embrace the same and movable away from the path to permit forward movement of the mandrel.

31. In a can making machine, a table, a flexible member extending therealong, a mandrel carried by the flexible member, anvil jaws movable toward the path of the mandrel to embrace the same and movable away from the path to permit forward movement of the mandrel, locating means for definitely positioning the mandrel for an operation to be performed on a can carried thereby, a shaft, means operable thereby for putting the locating means into operation, and means operable by the shaft for moving the anvil jaws toward or away from the path of the mandrel.

32. In a can making machine, a table adjustable to different positions, a flexible member extending along the table, a mandrel carried thereby, anvil jaws movable toward the path of the mandrel to embrace the same and movable away from the path to permit forward movement of the mandrel, a shaft extending in the direction of adjustment of the table, and means making a driving connection with the shaft at any adjusted position of the table for operating the anvil jaws.

33. In a can making machine, a mandrel, anvil jaws movable toward or away from the mandrel, drive means for moving the anvil jaws, and spring means in the driving connection so as to permit yielding of such jaws.

34. In a can making machine, a mandrel, an anvil jaw movable toward or away from the mandrel, a cam for effecting such movement, a shaft on which the cam is mounted, the cam being slidable on the shaft, and spring backing means for the cam.

35. In a can making machine, a ram, a cam for effecting a working stroke of the ram, and another cam for effecting a return movement thereof.

36. In a can making machine, a ram, a cam for effecting a working stroke of the ram, another cam for effecting a return movement thereof, and spring backed follower means for the last mentioned cam.

37. In a can making machine, a ram, a cam for effecting a working stroke of the ram, another cam for effecting a return movement thereof, and a single shaft on which the cams are mounted.

38. In a can making machine, a cap insert-

ing head having a flanging die, and a plunger for forcing a blank therethrough, and a mandrel adapted to support a can body in substantial alignment with the plunger, the plunger being arranged to carry the flanged cap into position in the can body.

39. In a can making machine, a cap inserting head having a flanging die and a plunger for forcing a blank therethrough, a mandrel adapted to support a can body in substantial alignment with the plunger, the plunger being arranged to carry the flanged cap into position in the can body, and stripper means for preventing withdrawal of the cap from the can body when the plunger is retracted.

40. In a can making machine, a blanking die for cutting blanks from sheet material, a flanging die, a plunger for forcing the blank therethrough, and a mandrel adapted to support a can body in substantial alignment with the plunger, the plunger being arranged to carry the flanged cap into position in the can body.

41. In a can making machine, a cap inserting head, feed means for supplying strip material thereto, a die in the head for forming a blank from the strip material, a flanging die in the head, a plunger for forcing the blank therethrough, and a mandrel adapted to support a can body in substantial alignment with the plunger, the plunger being arranged to carry the flanged cap into position in the can body.

42. In a can making machine, a cap inserting head, feed means for supplying strip material thereto, a die in the head for forming a blank from the strip material, a flanging die in the head, a plunger for forcing the blank therethrough, a mandrel adapted to support a can body in substantial alignment with the plunger, the plunger being arranged to carry the flanged cap into position in the can body, and shear means for cutting the scrap material.

In testimony whereof we have hereunto set our hands.

GEORGE O. FROSTAD.
JAMES E. ANNEN.
